(57) **CLAIM**

The ornamental design for a bag for carrying an animal, as shown and described.

DESCRIPTION

FIG. 1 is a front, right side, top perspective view of a bag for carrying an animal showing my new design;

FIG. 2 is a rear, left side, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a front, right side, top perspective view thereof, with the front closure rolled down.

The broken lines depict portions of the bag for carrying an animal which form no part of the claimed design.
